C. E. FIELD

VANITY CASE

Filed Feb. 9, 1925

Inventor

Clarence E. Field.

Oliver, Owen & Crampton
Attorneys.

UNITED STATES PATENT OFFICE.

CLARENCE E. FIELD, OF STOCKBRIDGE, MICHIGAN.

VANITY CASE.

Application filed February 9, 1925. Serial No. 7,751.

To all whom it may concern:

Be it known that I, CLARENCE E. FIELD, a citizen of the United States, and a resident of Stockbridge, in the county of Ingham 5 and State of Michigan, have invented a new and useful Vanity Case, which invention is fully set forth in the following specification.

This invention relates to containers and 10 particularly to so-called vanity cases for carrying rouge, powder, lip stick, puffs or other articles of toilet use.

Objects among others of this invention are to provide a new and improved replacement 15 element in a vanity case which is adapted to carry rouge or powder cakes or both; to provide a novel means for holding the replacement element in the case; and to provide a vanity case which is attractive in 20 appearance, is simple and compact, and has the new and improved features of construction and arrangement hereinafter described.

The invention is shown by way of illustration in the accompanying drawings, in 25 which,—

Figure 1 is a vertical sectional elevation of the vanity case;

Fig. 2 is a top plan view of the case with the parts opened;

Fig. 3 is an elevation of the replacement disk; and

Fig. 4 is a fragmentary sectional view of a modified form of the invention.

The vanity case shown for purposes of 35 illustration comprises an annular ring 1 to which the closure disks 2 and 3 may be connected by hinges 4, the closure disks cooperating with the ring 1 to snap into locked position as is usual in the case of closed face 40 watches. Attached to the inner face of the closure disk 2 and 3 respectively are mirrors 5 which may conveniently be held in place by inwardly projecting flanges 6 on the closure disks which are arranged to overlie 45 the mirrors. Each closure disk is adapted to receive a puff or dauber, a puff 7 being removably connected to the disk 2 by spring clip 8, and a puff 9 being removably connected to the disk 3 by a spring clip 10. The 50 puff 7 may be used for applying powder and the puff 9 for applying rouge.

Positioned substantially midway between the disks 2 and 3 and extending in a plane substantially parallel thereto is a disk or plate 11, the diameter of which is somewhat less than the inner diameter of the ring 1.

Adhesively connected to the disk 11 is a cake or compact 12 of powder and a compact 13 of rouge, each compact being surrounded by metal retaining ring 14. It is 60 to be understood that if desired instead of having compacts of dissimilar material on opposite faces of the disk 11 the compacts may be of similar material. Suitably secured to the disk 11 at diametrically opposed 65 portions are outwardly projecting attaching elements 15 and 16, the element 15 being arcuately shaped at its outer edge to extend into a similarly shaped groove 17 in the lower portion of the ring 1. The attaching 70 element 16 may be formed with a conically-shaped groove 18 to receive the end of a pointed, screw threaded stem 19, which is in threaded engagement with the ring 1 and is provided at its outer end with an outwardly 75 tapered ribbed actuating knob 20. The knob 20 is positioned in the socket of a cup-like member 21 fixed to the outer surface of the ring 1, and pivoted to the outer portion of the socket member 21 is a bail or handle 22 80 to enable the case to be readily carried on a ribbon or cord.

It will be apparent that the disk 11 may be readily removed from the vanity case for replacement or other purposes by opening 85 one of the closure disks, unscrewing the stem 19 by means of the knob 20 to move the pointed end thereof away from the socket or groove 18, and thereafter moving the disk slightly upwardly a sufficient distance for 90 the attaching element 15 to clear the groove 17, and then outwardly from the case. In this manner the case may be used continuously by merely replacing the disk 11 when 95 the compacts have been used up or depleted.

Under some conditions for the sake of enhancing the attractive appearance and for providing a more compact case the ring 1^a (Fig. 4) may be formed with a conical socket 23 to receive a similarly shaped 100 105 socket member 21^a which may be secured thereto in any usual or preferred manner; as indicated the bail 22^a may be pivoted to the socket member 21^a and of such shape as to occupy as little space as possible. Extending into the socket member 21^a is the head 24 of the screw threaded stem 19^a which is threaded into the ring 1^a and socket member 23, the head 24 having a knurled annular flange 25 to permit the stem to be 110 easily turned. This construction provides a most attractive looking case and simulates

closely the appearance of newer forms of watches, such resemblance and unique adjustment materially enhancing the selling value of the case, as will readily be appreciated.

An outstanding characteristic of the invention resides in the unique manner in which the compacts are supported within the case so that they may be positioned in a convenient position for use, but may readily and easily be removed for replacement without in any way injuring the case. This is a marked improvement over similar cases at present in use in which the compacts are ordinarily loose and are liable to be displaced and lost; obviously, in the present instance, after the compact has been initially positioned it will remain in place until further manipulation. Another feature consists in the ingenious construction which enables the case to be made very thin and therefore occupy but little space, and by having the case simulate a watch in appearance, an attractive novelty is provided.

Although I have shown and described a vanity case which is the best form known to me at the present time, it is to be understood that numerous changes in details of construction and arrangement in size and shape may be effected without departing from the spirit of the invention especially defined in the appended claims.

What I claim is:

1. A vanity case including three hingedly connected members, two of said members being closures for the opposite ends of the case, a relatively thin stationary plate connected to said third member, and adjustable means on said third member cooperating with said plate for removably connecting the plate thereto.
2. A vanity case including three hingedly connected members, two of said members being closures for the opposite sides of the case, a relatively thin disk carried by said third member, and an element on said third member operable from the outside of the case for removably connecting the disk thereto.
3. A vanity case including three hingedly connected members, two of said members constituting closures for opposite sides of the case, a relatively thin member carried by said third member and lying in a plane substantially parallel to said closure members, and a member carried by said third

member and movable in the plane of said relatively thin member for removably connecting said thin member thereto.

4. A vanity case including three hingedly connected members, two of said members constituting closures for opposite sides of the case, a relatively thin element carried by said third member and engaging said member at diametrically opposed portions, and a stem operable from the outside of the case and engaging one of said portions for removably connecting said element thereto.

5. A vanity case including three hingedly connected members, two of said members constituting closures for opposite sides of the case, a relatively thin disk engaging the third member at diametrically opposed portions and lying in a plane substantially parallel to said closure members, a socket member fixed to said third member, and a stem extending through said socket member and engaging the disk at one of said opposed portions thereby removably holding said disk in place.

6. A vanity case including three hingedly connected members, two of said members constituting closures for the opposite sides of the case, a relatively thin disk having oppositely projecting portions for engagement with the third member, face compacts adhesively connected to the opposite faces of the disk, and a member carried by said third member engaging one of said projecting portions for removably connecting the disk thereto.

7. In a vanity case having three hingedly connected members, two of the members constituting closures for opposite sides of the case, a disk connected to the third member, face compacts adhesively connected to opposite surfaces of the disk, and adjustable means on the third member for removably connecting said disc thereto.

8. A vanity case simulating in appearance a watch and having three hingedly connected members, two of said members constituting closures for opposite sides of the case, a thin flat disk connected to the third member, face compacts secured to the opposite surfaces of the disk, and means for removably connecting said disc to said third member.

In testimony whereof, I have hereunto signed my name to this specification.

CLARENCE E. FIELD.
